UNITED STATES PATENT OFFICE

2,672,196

TRIMMING AND WRAPPING MACHINE

William E. Gross, Joppa, Frank B. Hale, Bel Air,
and Irving C. Brown, Baltimore, Md., assignors
to the United States of America as represented
by the Secretary of War

Application April 13, 1936, Serial No. 74,048

15 Claims. (Cl. 164—42)

(Granted under Title 35, U. S. Code (1952),
sec. 266)

1

The invention described herein may be manufactured and used by or for the Government for governmental purposes, without the payment to us of any royalty thereon.

This invention relates to a trimming and wrapping machine adapted especially for trimming and wrapping relatively easily torn material such as filter paper.

A particular application of the invention is herein shown and described in connection with the trimming and wrapping of impregnated filter paper on a canister used to filter air for breathing. This paper is manufactured especially for this purpose and must have a great multiplicity of fine pores for efficient filtering and it therefore has relatively low tensile strength. The paper is preferably impregnated with activated charcoal, for example, to increase its filtering efficiency and is then trimmed and wrapped on an elliptical canister. This canister is adapted to contain air purifying chemicals within a perforated container, the filter paper being wrapped over the perforated wall of the canister. In order to obtain uniform filtering efficiency without excessive air resistance, it is necessary that the same number of layers of paper be placed on each canister.

One object of this invention is to provide a machine for drawing sheet material of low tensile strength therethrough and trimming the material and wrapping it on a form without tearing the material.

Another object of this invention is to provide a machine for trimming the edges of sheet material having low tensile strength without tearing when the material passes through the machine at variable speeds.

Another object of this invention is to provide a machine for trimming the edges of easily frangible filter paper and for wrapping a predetermined number of layers thereof around an air purifying canister, the machine being inexpensive to construct, not easily deranged, and capable of operation by unskilled operators.

Another object of this invention is to provide a trimming and wrapping machine in which the edge trimming knives always travel at the same speed as the material, so that a clean sharp cut is made even when easily frangible material is passed therethrough at variable speeds.

These and various other objects of the invention will be apparent from the following description and appended claims, it being understood that the invention is not limited to the details of construction herein set forth by way of illustration.

2

In the drawing,

Fig. 1 is a side elevation of the machine;

Fig. 2 is a front elevation thereof;

Fig. 3 is an enlarged detail from the left side

5 of the machine, parts being broken away;

Fig. 4 is a section on line 4—4 of Fig. 3;

Fig. 5 is an enlarged central section taken on

line 5—5 of Fig. 2;

Fig. 6 is an enlarged section on line 6—6 of

10 Fig. 3 showing the driving and driver rollers and

trimming knives;

Fig. 7 is a part section, part elevation of one

tension roller and its mounting;

Fig. 8 is a perspective view showing the canister

before receiving the wrapping; and

15 Fig. 9 is a similar view after wrapping of the

canister.

Referring to the drawings, the machine comprises a rectangular frame 1 preferably of angle iron construction having two open ended brackets 2 at the rear upper end to receive trunnions 3 upon which is mounted the roll 4 of paper. The roll of paper may be adjusted transversely of the machine by knurled screw collars 5 and 6 so that the correct amount may be trimmed from each edge. It will be understood that the paper is impregnated prior to the winding into roll 4, and this impregnating leaves a narrow strip on each side of the paper which is not impregnated. These two side portions of unimpregnated paper are trimmed off and discarded in the passage of the paper through the machine.

From the roll 4 the paper passes over guide roller 7 adjacent the upper front of the machine, beneath guide roller 8 and thence over drive roller 9 and downward. Roller 9 is preferably covered with a serrated rubber covering to prevent slipping of the paper. The trimming of the edges of the paper is accomplished as the same passes over roller 9 and circular knives 11 (see Fig. 6) are mounted on each end of roller 9. Cooperating circular knives are mounted on the adjacent shaft seen in Fig. 6, as hereinafter more fully described.

45 Roller 9 is secured to shaft 12 by end collars 13 and set screws 14, circular knives 11 being secured to these collars. Shaft 12 is supported in frame 1 by anti-friction bearings and projects beyond the frame at the left side of the machine and has a squared end to which is secured a ratchet 16. A cooperating pawl 17 is mounted on collar 18 which is secured to a pinion 19, collar 18 and pinion 19 being freely swiveled on shaft 12. Shaft 12 and roller 9 thereon may 50 thus be rotated in one direction by rotating pinion 19, the shaft being free to turn in the other

direction since pawl 17 will slip over ratchet 16. As seen in Fig. 3, pinion 19 meshes with gear 21 secured adjacent the left hand end of shaft 22 journaled in the frame, and having crank 23 secured on the right hand end thereof with a handle 24. Handle 24 is mounted on its crank 23 so that it may be reciprocated to the right, Fig. 2, so that pin 25 may be retracted out of the path of stop pin 26 on the frame of the machine, a coil spring within the handle normally forcing the handle and its pin 25 inwardly so that pins 25 and 26 will engage when crank 23 is rotated.

By the mechanism above described it will be seen that roller 9 may be rotated by turning 15 crank 23 by its handle 24. In the use of this machine, the paper is fed forward by one complete turn of crank 23, accomplished by retracting pin 25 to clear pin 26 and turning the crank until pins 25 and 26 engage. The drive is so proportioned that this movement feeds the paper forward the equivalent of one complete wrap or layer of paper on the canister.

Referring again to Fig. 6, a shaft 27 is journaled in antifriction bearings in the frame forwardly of shaft 12. Shaft 27 has secured thereto two sleeves 28 each having drive pulleys 29 with beveled edges in driving engagement with similarly beveled edges of pulleys 31 secured to shaft 12 by set screws or other securing means. Slidably mounted on sleeves 28 are two collars 32 to which are secured rotary knives 33 for engagement with knives 11 on roller 9. Knives 33 are pressed into engagement with knives 11 by a plurality of coil springs 34 which bear at their opposite ends against annular brackets 35 secured to sleeves 28.

From this construction it will be seen that rotary knives 33 are driven solely in accordance with the speed of the paper, so that the rotation of these knives will follow variations in paper speed. This is a feature of particular importance when trimming easily frangible material such as filter paper, since a variation between the paper speed and speed of rotation of the knives will tear rather than cut the paper.

In order to maintain tension of the paper against the roller 9, a pair of tension rollers 36 are spring-pressed against the paper to hold it against roller 9. The two rollers 36 are mounted on and secured to a shaft 37 (Fig. 7) which is loosely swiveled to a bracket 38. Bracket 38 has a cylindrical sleeve 39 whereby the bracket and rollers may be pivoted on a shaft 41 secured to the frame. A pin 43 threaded at opposite ends passes freely through an elongated slot 42 in bracket 38, one end of said pin being threaded to a collar 44 loosely mounted on the shaft 22, the opposite end having two lock nuts to retain a coil spring 45. It will thus be seen that the two rollers 36 are resiliently pressed against roller 9 with the paper therebetween.

The two sides cut from the paper as it passes over roller 9 are received in channel shaped troughs 46 which carry these edges to a waste receptacle.

From the roller 9, the trimmed paper drops past a cut-off device. In order that the paper may not follow the roller 9, it passes in front of a swinging bracket comprising two side arms 47 which are freely pivoted on shaft 22 and are connected at 70 their lower ends by a horizontal bar 48, thus forming a U-shaped bracket. As seen from Fig. 5, this bracket tends to swing outwardly with the lower bar 48 in engagement with the paper. This outward movement is limited by the engagement 75

of nuts 49 on rod 51 secured to bar 48 with a slotted stop 52 secured to the stationary frame.

Just below the bracket above described is stationary cut-off blade 53 and the horizontal movable blade 54. As seen in Fig. 2, the movable blade 54 is pivoted at 55 with its handle portion adjacent the right hand side of the machine. When cut-off knife is pressed inward to cut off a length of paper, the swinging bracket 47-48 pivots freely inward and then moves outward when pressure on the knife is relieved, to thus move the edge of the paper outward to an accessible position. A spring 60 is secured to the frame and to a portion of knife 54 projecting beyond the pivot 55 whereby the cut-off knife 54 is pressed outwardly to clear the paper.

Below the cut-off device is positioned a supporting means for the canister upon which the paper is wrapped. The canister 56, as seen in Fig. 8, is elliptical in cross section, and has a central portion of perforated mesh with recessed end portions 57 having overhanging flanges. Each canister is supported on the machine by heads which engage in the recessed portions of the heads 57. The head 58 at the left side of the machine, as seen in Fig. 4, is secured to a shaft 59 which is rotatably and reciprocatively mounted in the frame. Spring 61 surrounds shaft 59 and normally holds head 58 into engagement with head 57 of a canister.

Shaft 59 projects through the frame and has an undercut head 62 for engagement by one end of a bell-crank lever 63 pivoted to the frame at 64. The other end of lever 63 is connected by 35 rod 65, bell-crank lever 66, and rod 67 to a foot lever 68, Fig. 1. By pressure on foot lever 68, the head 58 may be retracted to remove a wrapped canister and replace it with an empty one.

Opposite the rotary head 58 is positioned a similar head 69 secured to a rotary shaft 72 which projects to the right of the machine and has a crank 73 thereon. A handle 74 is mounted on crank 73 similar to the mounting of handle 24, that is, the handle may be reciprocated in the crank against tension of a coil spring mounted therein to thereby move the inner end 75 of the handle shaft outwardly.

As heretofore indicated, it is desirable that a predetermined number of layers of filter paper be wrapped around each canister. In order that this may be automatically accomplished without requiring the operator to count the turns, the shaft 72 which turns the canister has a pinion 76 secured thereto which meshes with a gear 77 mounted on the frame. Gear 77 has a stop pin 78 thereon so positioned that it will engage the inner end 75 of handle 74. The pinion 76 and gear 77 are so proportioned that the stop pin 78 and handle 75 will engage after nine complete revolutions of a canister being wrapped. Obviously the relative sizes of pinion 76 and gear 77 or the position of stop pin 78 may be varied for different numbers of layers of paper as required.

Just below stationary cut-off blade 53 is positioned a plate 81 which guides the hanging paper into a position whereby it may be readily grasped by the operator for the initial wrap around the canister.

Operation.—The course of the paper around the rollers is indicated by the heavy line in Fig. 5, and in Fig. 1. When a roll of impregnated paper 4 is positioned in the forked frame members 2, the knurled pulleys or collars are adjusted to center the roll, there being provided a feeler

gauge not shown, against which one edge of the roll is positioned. The paper is then fed over roller 1, under roller 8, and over roller 9, and upper handle 24 is rotated to feed the paper until stops 25 and 26 engage. When the lower edge of the paper is slightly below cut-off knife 54, this knife is pressed inward and released to obtain an even edge and also to measure the correct amount of paper required for the canister.

Foot pedal 68 is then depressed to reciprocate canister head 58 outward and an empty canister such as seen in Fig. 8 inserted between heads 58 and 69, and lower handle 74 is turned until stops 75 and 78 engage.

Upper handle 24 is then pulled outward to clear movable stop 25 of stationary stop 26 and crank 23 is given one complete turn or until these stops engage. This feeds the paper forward the equivalent of one complete wrap on the canister.

Crank 23 turns shaft 22 and gear 21 which drives gear 19, pawl 17 and ratchet 16, thus rotating shaft 12 and roller 9. Pulleys 31 drive pulleys 29 to rotate knife shaft 27 at a speed directly proportional to the paper speed. The parts are so proportioned that the peripheral speed of knives 33 is the same as or greater than the peripheral speed of drive roll 9 and knives 11 mounted thereon.

There is thus no tearing of the edges even with relatively easily frangible material, since a clean cut is made by the knives.

One revolution of upper handle 24 moves the paper forwardly so that its lower end may be grasped and wrapped around the canister to the point A on Fig. 5 indicated by the termination of the heavy line representing the paper. The paper is held in this position with the left hand while the right hand grasps lower handle 74 which is reciprocated to clear stops 75 and 78. Crank 73 is then turned to directly rotate the canister and wind the paper thereon. The paper is thus pulled through the machine. Due to the elliptical shape of the canister, the paper advances at a constantly varying speed and the rotary knives 33 turn at a speed in direct proportion to the paper speed.

During this movement of the paper, the shaft 22 and handle 24 do not rotate, since the pawl 11 merely slips over its ratchet 16, and gears 19 and 21 do not turn. The edges of the paper fall into the troughs 46. When the requisite number of layers of the material have been wrapped, the stop 78 on gear 11 is in position to engage inner end of handle 75. In the present machine, this will be nine layers in addition to the one layer accomplished by rotation of handle 24. When these stops engage, the cut-off knife 54 is pressed in, swinging bracket 47-48 moving inward, and the operator grasps the end of the paper below the knife 54 and completes the wrapping. As indicated by the heavy dotted lines in Fig. 5, this paper is sufficient to extend slightly beyond the point A where wrapping was started, thus giving ten complete layers and a short overlap.

In order to prevent unwinding of the paper, a spring-pressed clip 82, Fig. 9, is slipped over the paper on the canister, and the wrapped canister removed by pressure on foot treadle 68. The machine is then ready for another operation. During its complete travel through the machine, the paper is maintained under sufficient tension by the rollers to prevent any slipping.

Although this invention has been described in connection with the trimming and wrapping of impregnated filter paper on a gas mask canister, it will be understood that the invention is not

limited thereto. Furthermore, it will be understood that the invention is not confined to the precise details of construction herein set forth by way of illustration, as it is apparent that many changes and variations may be made therein by those skilled in the art without departing from the spirit of the invention or exceeding the scope of the appended claims.

We claim:

1. A machine for trimming and wrapping sheet material on a form, comprising a roller over which the material passes, knives on the ends of said roller, cooperating rotary knives, means to draw the material over said roller to thereby rotate the same, and driving means between said roller and said cooperating knives whereby the rotary knives are driven at a speed directly proportional to the speed of the material; said driving means including resilient devices yieldably urging the rotary knives laterally into cooperative contact with the first mentioned knives.

2. A machine for trimming and wrapping sheet material, comprising a roller over which the material passes, knives on said roller, cooperating rotary knives, a form of non-circular cross-section upon which the material is wrapped, means for rotating said form to thereby draw the material over said roller at varying speeds and thereby rotate said roller, and driving means between said roller and rotary knives whereby said knives are rotated at a speed directly proportional to the speed of the material.

3. A machine for trimming and wrapping filter paper upon a canister, comprising a roller having knives thereon, cooperating rotary knives, a canister having a perforated wall about which the paper is wrapped, means for rotating said canister to thereby draw the paper over and rotate said roller, and means to rotate said rotary knives at a speed directly proportional to the speed of said paper.

4. A machine for trimming and wrapping filter paper upon a canister, comprising a roller having knives thereon, cooperating rotary knives, a canister of elliptical cross section having perforated wall about which the paper is wrapped, means for rotating said canister to thereby draw the paper over and rotate said roller, and a driving connection between said roller and said rotary knives whereby said knives will rotate at a speed directly proportional to the varying speed of the paper.

5. A machine for trimming and wrapping sheet material upon a form, comprising a roller having knives thereon, cooperating rotary knives, means to rotate said roller a predetermined amount to thereby advance the material, a rotatably mounted form upon which the material is to be wrapped, means to rotate said form and draw the material over and rotate said roller, and driving means between said roller and said rotary knives whereby said knives are rotated at a speed directly proportional to the speed of the material irrespective of which drive advances the material.

6. A machine for trimming and wrapping sheet material upon a form, comprising a plurality of rollers over which the material passes, rotatable trimming knives, a rotatable form upon which the material is wrapped, means for rotating one of said rollers to thereby advance the material, means to rotate said form to draw the material through the machine by wrapping on the form, and means to rotate said trimming knives at a speed proportional to the speed of the material.

7. A machine for trimming and wrapping sheet material upon a form, comprising a plurality of

rollers over which the material passes, a rotatable form upon which the material is wrapped, a crank to rotate one of said rollers to advance the material, mechanism to stop rotation of said crank after the material advances the equivalent of one layer on said form, a crank for rotating said form, and mechanism to stop rotation of said last-named crank after a predetermined number of layers of material have been wrapped on said form.

8. A machine for trimming and wrapping filter paper on an air purifying canister, comprising a plurality of rollers around which the paper passes, rotary knives whereby the edges of said paper are cut off as the paper passes around the 15 rollers, a rotatable support for a canister, means to rotate one roller to advance the paper, mechanism to stop said means after the paper has advanced the equivalent of one layer on said canister, means to rotate said canister support 20 whereby the paper may be drawn through the machine and wrapped on the canister, and mechanism to stop said last-named means after a predetermined number of layers have been wrapped on the canister.

9. The invention as defined in claim 8 characterized in that said rotary knives are always driven at a speed proportional to the movement of the paper.

10. In a machine for trimming and wrapping easily frangible material, a roller over which the material passes, a shaft to which said roller is secured, knives on said roller, a knife shaft, rotary knives secured to said knife shaft and in cooperative engagement with the knives on said roller, and driving mechanism between said roller shaft and said knife shaft whereby the rotary knives are driven at a speed proportional to the movement of the material.

11. In a machine for trimming filter paper and wrapping layers thereof around an air purifying canister, means for supporting a roll of filter paper, rotary supporting means for a canister to be wrapped with the filter paper, means intermediate the roller and canister supports for trimming opposite edges of the paper as the latter advances toward the canister support, means for advancing the paper the equivalent of one layer on the canister, additional means for continuing advancement of the paper to complete 50 the application of a predetermined additional number of layers to the canister, including means for checking rotary movement of the canister support at the end of each complete wrapping operation, and means intermediate the edge-trimming means and rotary canister support for severing the filter sheet upon completion of each wrapping operation.

12. In a device for wrapping filter paper upon an air purifying canister, a support for a roll of 60 such paper, a rotary support for the canister to be wrapped and provided with means for checking rotary movement of said support upon com-

pletion of each wrapping operation, and means for advancing the paper from the roll toward said support to engage the paper with the canister for initiating the wrapping operation and including means limiting such advancement of the paper to an extent equivalent to one layer of the complete wrapping.

13. In a device for wrapping filter paper upon an air purifying canister, means for supporting a roll of such paper, a rotary support for the canister to be wrapped, and including means for checking rotary movement of the support at the end of each complete wrapping operation, means for advancing the paper from the roll toward said support to facilitate engaging the paper with the canister to initiate the wrapping operation, and including means limiting such advancement of the paper to an extent equivalent to one layer of the complete wrapping, and means in advance of the rotary support for severing the paper from the roll at the end of each wrapping operation.

14. In a machine for trimming and wrapping sheet material, means for trimming the edges of a web, a rotary support for an article about which the trimmed web is to be wrapped, means for checking rotary movement of said support at the end of each wrapping operation, and means disposed intermediate the edge-trimming means and the rotary support for severing the web at the end of each wrapping operation.

15. In a machine for wrapping filter paper about a canister, means for severing the paper upon completion of the wrapping operation and embodying a vertically swingable, substantially U-shaped bracket between the legs of which the paper is trained to feed, and a pivotally supported cut-off knife swingable in a substantially horizontal plane toward and away from said bracket in effecting a severing of the paper; and said bracket being freely movable inward incidental to the cutting operation and then outward upon completion of such operation to move the edge of the severed paper to a readily accessible position.
